The ornamental design for a personal warming apparatus, as shown and described.

DESCRIPTION

FIG. 1 is a front view of a personal warming apparatus showing our new design;

FIG. 2 is a rear view thereof;

FIG. 3 is a top view thereof;

FIG. 4 is a bottom view thereof; and,

FIG. 5 is a right-side view thereof, the left-side view being a mirror image.

CERTIFICATE OF CORRECTION

PATENT NO. : D627,076 S
APPLICATION NO. : 29/352969
DATED : November 9, 2010
INVENTOR(S) : Atsushi Matsuo et al.

Page 1 of 3

It is certified that error appears in the above-identified patent and that said Letters Patent is hereby corrected as shown below:

The title page should be deleted to appear as per attached title page.

The sheet of drawings consisting of figure 3 should be deleted to appear as per attached figure 3.

Signed and Sealed this
Twenty-seventh Day of September, 2011

David J. Kappos
Director of the United States Patent and Trademark Office
